UNITED STATES PATENT OFFICE.

WILLIAM T. FINNEGAN, OF DETROIT, MICHIGAN.

AUTOMATIC WINDOW-LOCK.

1,314,794.

Specification of Letters Patent.

Patented Sept. 2, 1919.

Application filed August 8, 1918. Serial No. 248,927.

To all whom it may concern:

Be it known that I, WILLIAM T. FINNEGAN, a citizen of the United States, residing at Detroit, in the county of Wayne and State of Michigan, have invented certain new and useful Improvements in Automatic Window-Locks; and I do declare the following to be a full clear, and exact description of the invention, such as will enable others skilled in the art to which appertains to make and use the same.

This invention relates to window sash fasteners, and it relates more particularly to an improved automatic window sash lock. One of the objects of the invention is to provide a device of this character which automatically locks both sashes in the closed position or open position or in partly open position.

Another object is to provide a device of this character in which any attempt to raise the lower sash or to lower the upper sash, while locked, serves to lock both sashes more securely.

Another object is to provide a device of this character in which the elements that lock the upper and lower sashes, respectively, are interdependent and are operated by an automatic actuator that is common to both, and are released by a single manipulative element or lever.

Another object is to provide a sash lock of this character that is strong, durable, compact, convenient and easily attachable to any window of ordinary construction, and

Another object is to provide a device of this character which consists of few and simple parts, and therefore may be manufactured at a comparatively low cost.

Other objects and advantages may become apparent to persons who read the following details of description in connection with the accompanying drawings, in which:

Figure 1 is a side elevation of my improved window sash lock secured to the upper end of a lower sash and frictionally engaging the inner side of the upper sash.

Fig. 2 is a horizontal sectional view along the line 2-2 of Fig. 3.

Fig. 3 is a vertical view along the line 3-3 of Fig. 5, the working parts being shown in elevation and in the operative position.

Fig. 4 is a view similar to Fig. 3, except that the working parts are in inoperative position.

Fig. 5 is a top plan view, the parts being shown in the operative position, and

Fig. 6 is a transverse vertical sectional view along the line 6-6 of Fig. 3.

Referring to these drawings, in detail, in which similar reference characters correspond with similar parts throughout the several views, a casing or base 10 is provided with a flange 11 which is apertured at 12 for the reception of screws 13, whereby it may be secured to the top of the lower sash as indicated in Figs. 1, 2, 5 and 6. Although I show this base or casing with a flange 14 which extends in the same horizontal plane with the flange 11, and constitutes a bottom of the base or casing 10, this flange 14 may be dispensed with for the sake of economy. The casing 10 is here shown with slotted end walls 15 and 16, but these end walls may also be dispensed with for the sake of economy in the manufacture of the device. The essential features of the casing 10 are the vertical walls 17 and 18, the flange 11 and a horizontal top or cap-plate 19.

Between the walls 17 and 18 are mounted three levers 20, 21 and 22, these levers being pivotally mounted on pintles 23, 24 and 25, respectively, which extend through the side walls 17 and 18, and are supported thereby; and these pintles are preferably headed and screw-threaded so as to support the walls in proper relation with one another, and are preferably removable for the sake of making any necessary repairs.

A sash-engaging element 26 is secured to the outer end of the lever 20 by means of a securing member 27, and these elements 26 and 27 may be properly considered as parts of the lever 20. This lever is longitudinally slotted at its middle part as indicated at 28, and the lever 21 is provided with a stud 29 which extends through the slot 28 so as to operatively connect the levers 20 and 21 in such relation that the swinging of either of these levers effects a corresponding movement of the other. These levers are normally held in the operative position shown in Figs. 1, 2, 3 and 5 by means of a spring 30 which is preferably formed of wire and is coiled around the pintle 23, and is formed with arms 31 and 32, the arm 31 being in the form of a loop which engages with the top part of lever 20 and presses downward thereon, the arm 32 being engaged with the cap-plate 19.

The lever 21 is provided with a lateral extension or dog 33 which has a somewhat sharp upper edge that engages with the inner window stop or sash-retaining strip, as shown in Figs. 2 and 3, when the lever 21 is depressed, but which releases its engagement with this element of the window frame when the levers 20 and 21 are swung upward.

The lever 22 is provided with a lateral element or wing 34 which rests against the lower side or edge of the lever 20, and the lever 22 is also formed with a wing or handle 35 whereby this lever may be swung on its pivot so as to raise the lever 20 by means of the wing 34, as shown in Fig. 4.

It is contemplated to manufacture these window locks in different sizes corresponding to the standard thicknesses of window sashes, so that when they are properly secured on the respective lower sashes, the frictional element 26 engages with the upper sash while the dog 33 engages with the element of the window frame which holds the lower sash in place and constitutes the inner guide therefor.

The several parts of the device, with the exception of the spring, pintles, rivets and rubber element 26, are preferably formed of sheet metal blanks or stampings, thereby enabling the device to be manufactured at the minimum cost.

In applying the device to a window, the lever 22 is depressed so as to raise and restrict the free ends of the levers 20 and 21; the device is now placed on the lower window sash adjacent to the window frame, so that the dog 33 is between the window stops or strips; the lever 22 is now released, so that the spring 30 co-operates with the stud 28 for depressing the levers 20 and 21, thus causing the elements 26 and 33 to engage, respectively, with the upper sash and inner sash stop or strip, and the screws 13 are now forced into the lower sash, through the openings of the flange 11. It will be seen, therefore, that this device is self-adjusting as regards its position transversely of the lower sash and when it is secured in this self-adjusted position, the levers 20 and 21 have perfect co-operation in preventing the raising of the lower sash and the lowering of the upper sash. In this connection, it will be seen that any attempt to lower the upper sash effects a tighter engagement of the frictional elements 26 therewith; and that any attempt to raise the lower sash effects a tighter engagement of the dog 33 with the window frame. Moreover, it will be seen that any movement of the upper frame which effects an additional movement of the lever 20 also effects an additional movement of the lever 21 so as to lock the lower sash more securely, and that any movement of the lower sash effects an additional downward movement of the lever 21 and also

lowers the lever 20 so as to increase the security of the upper sash.

Although I have described this embodiment of my invention very specifically, it is not intended to limit this invention to these exact details of construction and arrangement of parts, but I am entitled to make changes within the scope of the inventive idea disclosed in the foregoing description and following claims.

75

I claim

1. In a window-sash fastener, the combination with a window frame and sashes, of a base secured to the top of the lower window-sash and extending substantially from the inner side to the outer side of said sash, a lever having one end pivotally mounted on the base, said lever extending outward substantially from one side to the opposite side of the base and having its other end normally extending to the inner surface of the upper sash at a level considerably above the pivotal connection of the first said end, elastic means to press said other end downward and yieldingly hold it in engagement with the upper window-sash, retaining means supported by said base and movable into and out of engagement with the window frame, and means common to said lever and the said retaining means and being operable to release said lever and said retaining means from their engagement with said upper sash and window frame.

2. In a window sash fastener, the combination with a window frame and sashes, of a base secured to the top of the lower window-sash, a lever having one end pivotally mounted on the base and extending outwardly thereacross and having its other end normally extending to the inner surface of the upper sash at a level considerably above the pivotal connection of the first said end, means to press said other end downward and yieldingly hold it in engagement with the upper window-sash, a lever pivotally supported by said base and being longitudinally disposed in a plane parallel with the length of the first said lever and being movable into and out of engagement with a sash-stop of the window-frame, and means common to the first and second said levers and being operable to release said levers from their engagement with said upper sash and window-frame.

3. In a window-sash fastener, the combination with a window frame and sashes, of a base secured to the top of the lower window-sash, a lever having one end pivotally mounted on the base extending outwardly thereacross and having its other end normally extending to the inner surface of the upper sash at a level considerably above the pivotal connection of the first said end, a lever having one end pivotally mounted on said base adjacent to the outer side of the

125

130

- lower sash and having its inner end on a considerably higher level than its outer end, means operatively connecting the middle parts of these levers so that a movement of one lever will be transmitted to the other lever, means to yieldingly hold the first and second said levers in engagement respectively with the upper sash and window frame, and means to release these levers from such engagement.
4. In a window sash fastener, the combination with a window frame and sashes, of a base secured to the top of the lower window-sash, a lever having one end pivotally mounted on the base and extending outwardly thereacross and having its other end normally extending to the inner surface of the upper sash at a level considerably above the pivotal connection of the first said end, a lever having one end pivotally mounted on

- 10
- 15
- 20
- said base adjacent to the outer side of the lower sash and having its inner end on a considerably higher level than its outer end, means operatively connecting the middle parts of these levers so that a movement of one lever will be transmitted to the other lever, means to yieldingly hold the first and second said levers in engagement respectively with the upper sash and window-frame, and an actuating lever pivotally mounted below the middle portions of the first and second said levers and having one end extended laterally under the first said lever.
- In testimony whereof I have hereunto set my hand.

WILLIAM T. FINNEGAN.
